US00D995496S

(12) **United States Design Patent** (10) **Patent No.:** **US D995,496 S**
(45) **Date of Patent:** **** Aug. 15, 2023**

(54) **PROJECTOR**

(71) Applicants: **Deli Liu**, Shenzhen (CN); **Xionghui Chen**, Shenzhen (CN)

(72) Inventors: **Deli Liu**, Shenzhen (CN); **Xionghui Chen**, Shenzhen (CN)

(**) Term: **15 Years**

(21) Appl. No.: **29/807,088**

(22) Filed: **Sep. 9, 2021**

(51) LOC (14) Cl. **16-02**

(52) U.S. Cl.

USPC **D16/230**

(58) **Field of Classification Search**

USPC D14/225; D16/230-231, 221

CPC G03B 27/56; G03B 21/28

(57) **CLAIM**

The ornamental design for a projector, as shown and described.

DESCRIPTION

FIG. 1 is a perspective view of the projector showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures depict portions of the projector that form no part of the claimed design.

1 Claim, 8 Drawing Sheets
